US0D1088618S

(12) **United States Design Patent** (10) Patent No.: **US D1,088,618 S**
(45) Date of Patent: ** Aug. 19, 2025

(54) **BEVERAGE CAN STORAGE RACK**

(71) Applicant: **Ningbo Qisen Technology Co., Ltd,**
Zhejiang (CN)

(72) Inventors: **Zhuan Xia**, Zhejiang (CN); **Meng Wang**, Zhejiang (CN)

(73) Assignee: **Ningbo Qisen Technology Co., Ltd,**
Ningbo (CN)

(**) Term: **15 Years**

(21) Appl. No.: **29/982,497**

(22) Filed: **Jan. 6, 2025**

(30) **Foreign Application Priority Data**

Jul. 5, 2024 (CN) 202430420883.6

(57) **CLAIM**

The ornamental design for a beverage can storage rack, as shown and described.

DESCRIPTION

FIG. 1 is a front, left, and top perspective view of a beverage can storage rack showing our new design;

FIG. 2 is a rear, right, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the beverage can storage rack that form no part of the claimed design.

1 Claim, 8 Drawing Sheets
